(57) **CLAIM**

The ornamental design for a rectangular utility baking pan, as shown and described.

DESCRIPTION

As shown in the appended drawings, the ornamental design of my invention is directed to bakeware having decorative textured surfaces comprising a raised diamond pattern on the inner (food contacting) surface and an indented diamond pattern on the exterior surface thereof.

FIG. 1 is a perspective view of a rectangular utility baking pan of the present invention;

FIG. 2 is an enlarged view of the pattern shown in area 2 in FIG. 1.

FIG. 3 is an enlarged view of the pattern shown in area 3 in FIG. 1.

FIG. 4 is a top plan view of the rectangular utility baking pan of FIG. 1;

FIG. 5 is a side elevation view of the rectangular utility baking pan of FIG. 1;

FIG. 6 is an end elevation view of the rectangular utility baking pan of FIG. 1; and,

FIG. 7 is a bottom plan view of the rectangular utility baking pan of FIG. 1.
